(57) **CLAIM**

The ornamental design for a mobile communication device holder, as shown and described.

DESCRIPTION

FIG. 1 is a front perspective view of a mobile communication device holder showing the new design; FIG. 2 is a front elevational view thereof; FIG. 3 is a rear elevational view thereof; FIG. 4 is a rear perspective view thereof; FIG. 5 is a left-side elevational view thereof; FIG. 6 is a top plan view thereof; FIG. 7 is a bottom plan view thereof; FIG. 8 is a front elevational view thereof showing the mobile communication device holder in a state of use with an environmental mobile communication device; and, FIG. 9 is a rear elevational view thereof showing the mobile communication device holder in a state of use with an environmental mobile communication device.

The broken lines in the drawing figures depict an environmental mobile communication device and portions of the mobile communication device holder that form no part of the claimed design.

1 Claim, 7 Drawing Sheets
